UNITED STATES PATENT OFFICE.

ISAAC J. HARTFELD, OF ROCHESTER, NEW YORK, ASSIGNOR TO J. Y. MCCLINTOCK, OF ROCHESTER, NEW YORK.

PROCESS AND APPARATUS FOR LAYING PAVEMENTS.

1,198,631.

Specification of Letters Patent. Patented Sept. 19, 1916.

Application filed February 27, 1914, Serial No. 821,512. Renewed August 9, 1916. Serial No. 114,063.

To all whom it may concern:

Be it known that I, ISAAC J. HARTFELD, a citizen of the United States, residing at Rochester, in the county of Monroe and 5 State of New York, have invented certain new and useful Improvements in Processes and Apparatus for Laying Pavements, of which the following is a specification.

The object of this invention is to provide 10 a new and improved form of apparatus with which to lay pavements made up with blocks of uniform size.

Another object of this invention is to provide 15 a new and improved process by which pavements may be laid with blocks of uniform size.

These and other objects of the invention 20 will be fully illustrated in the drawings, described in the specification and pointed out in the claims at the end thereof.

In the accompanying drawings, Figure 1 is a perspective view of my improved pallet or tray. Fig. 2 is a sectional view of the tray, section being taken on the line 2^x—2^x 25 of Fig. 1. Fig. 3 is a detail view of the rake. Figs. 4 and 5 are plan views of the road that may be laid by the use of the pallet. Fig. 6 is a view of the road with the pallet in the act of laying. Fig. 7 is a 30 plan view of the right hand pallet. Fig. 8 is a plan view of the left hand pallet.

This invention has for its purpose more especially the laying of pavements or roads such as is described in the patent to J. Y. 35 McClintock, No. 957,985, and has for its object the facilitating and cheapening of the laying of the road made up of small blocks of uniform size. To this end, the pallet has a floor 1, on one side of which is a flange 2 40 which runs the full length thereof. Below the pallet are shoes 3 which are preferably made of metal having the upturned end 4 in which is provided the hand hole 5. These shoes rest on the ground. They are prefer- 45 ably tapered so as to give the pallet a slight forward inclination. In connection with this pallet I also provide a rake 6 having a handle 7, having end members 8 and 9 fastened directly to the cross bar 10 and indi- 50 rectly through the braces 11 and 12. A second cross bar 13 is also used for the purpose of strengthening it.

The use of my invention may be described 55 as follows: After the road bed is prepared, the blocks or cubes which are preferably of

about two or two and a quarter inches each way, are dumped along the side of the road. If the road is sixteen feet in width, these pallets will be preferably made each five feet, four inches long so that three of them 60 placed end to end will equal the width of the road. Each of these pallets will be operated by two men who will carry it first to a pile of cubes and will put it on the ground or on a suitable stand and will then lay preferably four rows of cubes on the pallet each 65 row of cubes extending the whole length of the pallet. In other words when the pallet is loaded, there will be on the pallet, four parallel rows of cubes, five feet four inches 70 long. The operators will then carry the pallet to the road and place the forward edge of the pallet on the blocks that have already been laid in the road. A third operator, placed on the road that has already 75 been laid, is provided with a rake shown in Fig. 3 and he will place the cross bar 10 of the rake on top of the flange 2 of the pallet taking hold of the row of cubes farthest from him and hold the cubes, drawing them 80 against the cubes that have already been laid in the road. The two operators of the pallet will then draw the pallet out from under the cubes, permitting the cubes to drop into the road in place. The operators 85 will then carry their pallet to a pile of cubes and fill it again and repeat this operation, three pallets serving to lay a section of the road the full width of the road and four 90 rows long, the cubes or blocks being raked from each pallet by the rake shown in Fig. 3.

It will be understood that the number of pallets used may be five or six or even more and a single rake such as shown in Fig. 3 95 may be used for all of said pallets, one operator with the rake being capable of drawing the cubes off of the pallets as fast as five or six or even ten pairs of men can handle the pallets.

As above described, the apparatus will be used in laying the blocks or cubes where the rows run at right angles to the center lines of the road. It is in many cases necessary or even desirable to lay the blocks in rows that run diagonal to the center line of the road and for this purpose special pallets would be provided for laying the outer border of the highway. For this purpose a right and left hand pallet must be provided 100 105 110

and one end of the pallet must be cut off on an exact miter, the other end of the pallet being left square. The square end of the pallet will always be placed toward the center of the road in laying the cubes. The mitered end will be laid to the edge or shoulder of the road and the miter must lie parallel to the middle line of the road. The right hand pallet will be used for laying the outer course of blocks on the right hand side of the road. The left hand pallet will be used for laying the outer course of blocks on the left hand side of the road, while the pallets such as shown in Fig. 1 will be used for laying the intermediate courses of blocks.

As shown in Fig. 5, the blocks are laid in rows which are at angles of 30° and 60° to the middle line of the road. The ends of the pallets used for laying these blocks would be cut at an angle of 30° to correspond and the pallets cut with such angles are shown in Figs. 7 and 8.

It will be understood that the angle might be 45° instead or any other one that might be desired and the pallets would be cut to correspond.

I claim:

1. A paving tool comprising a pallet adapted to support horizontal rows of small paving blocks of substantially uniform size, said pallet having a flange extending upwardly along one side thereof, and means adapted to extend longitudinally along the flanged side of the pallet and to operate over the pallet transversely for removing the assembled blocks without substantial derangement of their formation.

2. A paving tool, comprising a pallet adapted to support horizontal rows of small paving blocks of substantially uniform size, said pallet having a flange extending upwardly along one side thereof and said pallet having inclined shoes on its bottom, and means adapted to extend longitudinally along the flanged side of the pallet and to operate over the pallet transversely for removing the assembled blocks without substantial derangement of their formation.

3. A paving tool comprising a pallet adapted to support horizontal rows of small paving blocks of substantially uniform size,

said pallet having a flange extending upwardly along one side thereof, and a rake operable over the pallet having a flange to rest on the flange thereof and to engage with the blocks which project beyond the flange of the pallet.

4. A paving tool comprising a pallet adapted to support horizontal rows of small paving blocks of substantially uniform size, 60 said pallet having a flange extending upwardly along one side thereof, and said pallet having one of its ends mitered and adapted to be arranged substantially parallel to the middle line of the roadway, and means 65 adapted to extend longitudinally along the flanged side of the pallet and to operate over the pallet transversely for removing the assembled blocks without substantial derangement of their formation. 70

5. A paving tool, comprising a pallet adapted to support horizontal rows of small paving blocks of substantially uniform size, 75 said pallet having a flange extending upwardly along one side and having one of its ends square and the other end mitered and adapted to be arranged substantially parallel to the middle line of the roadway, and means adapted to extend longitudinally along the flanged side of the pallet and to 80 operate over the pallet transversely for removing the assembled blocks without substantial derangement of their formation.

6. The process herein described of laying a pavement, which consists in first preparing a suitable foundation, arranging small cubical paving blocks of substantially uniform size in rows upon pallets, placing said pallets in position on the road and raking the rows of blocks from said pallets by 85 holding the blocks against movement and withdrawing the pallets thereby permitting the blocks to drop into place in the road without substantially disturbing their arrangement. 95

In testimony whereof I affix my signature in presence of two witnesses.

ISAAC J. HARTFELD.
